UNITED STATES PATENT OFFICE

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

CUTTING MACHINE

Application filed June 15, 1925. Serial No. 37,185.

This invention relates to cutting machines and is herein illustrated as embodied in a machine designed for shaping the heel ends of shoe sole blanks.

5 In the manufacture of Goodyear welt shoes, it has been customary to employ what are termed "blocked soles", that is, soles which are not shaped even approximately to the desired final peripheral contour at the heel 10 and toe ends before attachment to the shoes, but are made square at the ends. This invention provides an improved machine adapted for cutting the heel end of a blocked sole, before attachment to a shoe, to substantially the desired final size and peripheral 15 contour. A sole so treated has the advantage, for example, that the shaped rear end of the sole will then furnish an accurate gaging surface which may be utilized in the manner set 20 forth in United States Letters Patent No. 1,382,689, granted June 28, 1921, on my application, for controlling the shank skiving, or "shanking-out" operation as it is frequently termed, so that the skiving will be located 25 more accurately with relation to the heel end of the sole.

In accordance with a feature of the invention, the illustrated machine is provided with a plurality of open dies of different sizes 30 adapted for dieing out the heel ends of blocked soles before the soles are attached to shoes, and arranged so that any one of the dies may be readily moved from an inoperative position to a position in operative relation to a sole on a work support. Preferably, and as 35 illustrated, the machine is provided with gaging means for accurately positioning soles on the work support. Advantageously too, the dies have outturned ends which act to cut off waste pieces of material resulting from the dieing-out operations. By the use of such a dieing-out machine, the heel ends of blocked soles may be quickly and accurately shaped, whatever their sizes, without the necessity of 40 substitution of parts or of time-consuming 45 adjustments.

To insure that the machine will not be operated unless a die is positioned in operative relation to the work support, another feature 50 of the invention consists in the provision of

novel means acting automatically to lock the machine against operation if the operator attempts to actuate the machine without first bringing a die into operative position relative to the work support, thus safeguarding 55 against damage to the dies and work support and against mutilation of the work.

With a view to facilitating removal of the waste or chips resulting from the dieing-out operations, in accordance with another feature of the invention, in the illustrated machine a member of the sole gaging means is utilized to remove the material cut from the sole blank. As illustrated, a sole positioning member, which facilitates positioning the sole 60 initially and is retracted from contact with the sole before the heel end of the sole is died out, has imparted to it thereafter movement 65 across the line of cut and back in such manner as to engage the scrap material and pull it 70 away from the sole.

Although the invention is herein illustrated as embodied in a machine comprising a plurality of dies adapted to be used interchangeably to die out the heel ends of blocked 75 soles, it should be understood that in various respects the invention is not limited to embodiment in such an organization, or to use in shaping the heel ends of soles, but may be embodied to advantage in machines of 80 other types and in machines for performing other similar operations.

In the accompanying drawings,

Fig. 1 is a side elevation of one embodiment 85 of my invention;

Fig. 2 is a rear elevation, partly in section, of the die block, turret and driving connections therefor, according to my invention;

Fig. 3 is a plan view showing the work positioning and holding devices; 90

Fig. 4 is a perspective view of the turret, clutch and locking devices therefor;

Fig. 5 is a perspective view showing in detail a portion of the mechanism for adjusting 95 the work positioning devices;

Fig. 6 is a cross-section in detail of the device for adjusting the heel gage;

Fig. 7 is a detail of the pin-and-slot structure shown in Fig. 6; and

Fig. 8 is a detail of the heel gage. 100

The machine illustrated in the drawings is adapted for dieing out the heel end of a blocked sole to substantially the desired final peripheral size and contour. Such a sole blank is shown at 10 (Fig. 3 of the drawings), the dotted line 10' indicating the shape of the heel end of the blank after an operation has been performed by the machine. The illustrated machine comprises a frame 11 (Figs. 1 and 2) supporting a bed 12, to which are bolted four standards 14 and 16. Mounted for reciprocation on the standards 16 is a turret 18 carrying a plurality of dies 20 of different sizes. The turret 18 is manually rotatable so that a selected die may be brought into alignment with a blank on a die block 22 to effect an operation on the blank upon reciprocation of the turret. The blank to be operated on is positioned on the block 22 by means of side gages 24, 26 (Fig. 3) and a heel gage 28, and during the dieing-out operation is clamped to the block by means of a presser foot 30.

The turret 18 (Figs. 1 and 2) is mounted on a rotatable shaft 32 supported on sleeves 34 slidably on the guides or standards 16. Reciprocating movement of the turret is obtained by means of arms 36, each of which is operatively connected at one end to the shaft 32, the other end being eccentrically mounted on a drive shaft 38 which is carried in bearings 40 supported by the standards 16 and by the standards 14. The drive shaft 38 is arranged for operative connection to a fly-wheel 42 driven by an electric motor 44, by means of a clutch mechanism 46 (Fig. 4) which is of the one-revolution type. Depression of a treadle 48 actuates a starting lever 50 by means of a link 52 to release a clutch pin 54 which operatively connects the drive shaft 38 to the fly-wheel 42. Rotation of the drive shaft 38 causes a downward movement of the eccentric arms 36, effecting a dieing-out operation of the turret. Further rotation of the drive shaft raises the turret, and a cam 56 moves outwardly a roll 58 on an arm 60 of link 52, placing the starting lever 50 in clutch-releasing position, thereby disconnecting the drive shaft from the fly-wheel at the end of 50 a single revolution of the drive shaft.

For conveniently rotating the turret to adjust the position of the dies with respect to the die block 22, a hand-wheel 62 is attached to the end of the shaft 32.

Mechanism is provided for locking the turret 18 in such position that any one of the dies 20 may be locked in operative relation to the die block. This mechanism comprises a plate 64 (Figs. 2 and 4) mounted to turn with the shaft 32 and provided with notches 66 corresponding in number to the dies 20. A detent 68 carried by one of the sleeves 34 and manually operable by a lever 70 is arranged for engagement in one of the notches 66 when the die corresponding thereto has been ro-

tated into operative alignment with the die block, thus locking the selected die in operative position. If for any reason the selected die has not been placed in operative position, the detent 68 will not enter any of the notches 66, but will be supported on the periphery of the plate 64. In such case, a dog 72 integrally connected to the detent 68 will contact with a stop 74 of the starting lever 50, preventing rotation thereof and thereby locking the starting mechanism against such operation as would initiate a reciprocation of the turret 18.

The dies 20 flare outwardly at each of the open ends thereof, as shown at 21, Fig. 2, in such manner as to cut off the waste pieces resulting from the dieing-out operation.

The die block 22 is carried by a member 76 having a sleeve 78 integral therewith slidably mounted in the casting 80 forming an extension of the bed 12. To secure adjustment of the die block 22 with relation to the turret 18 as the block wears down, a screw 82 is provided for engaging the sleeve 78 to raise or lower the block supporting member 84 upon rotation of a hand-wheel 84.

In order that the block 22 may wear evenly under the action of the dies, provision is made for rotating the block after each dieing-out operation. To this end the upper surface of member 76 is provided with a toothed rack 86 (Figs. 3 and 5) which is moved by a pawl 88 through a small arc by mechanism which will be hereinafter described.

The blank to be operated on is positioned on the block 22 by means of the ball line gages 24 (Fig. 3), the breast line gages 26 and the heel gage 28.

The gages 24 by means of the links 90 are connected with toothed links 92 pivoted on a plate 94 carried by the bed 12. The gages 24 are urged toward each other by the tension of a spring 96 and are positioned to contact with the forepart of the blank at the ball line and secure alignment of the forepart with the center line of the heel gage 28. Adjustment of the gages 24 for different widths of blanks may be made by means of a set-screw 98 which bears against one of the links 92. The set-screw 98 also acts as a stop for limiting inward movement of gages 24. The gages 26 complete the alignment of the blank laterally of the block by contacting with the blank at the heel breast line and moving the heel end of the blank into alignment with the center line of the heel gage. The gages 26 are pivotally mounted on the bed 12 and are normally urged toward each other by a spring 100. The gages 26 are adjusted for different widths of blanks by means of the set-screw 102 mounted on the rock-shaft 104 and which bears on the lug 106 on one of the gages. Inward movement of gages 26 is limited by an adjusting screw 108 carried by an arm 110 on the shaft 104.

and bearing on a portion of the frame. For a more complete description of the construction and operation of gages 24 and 26 as so far set forth, reference may be made to United States Letters Patent No. 1,382,689, granted June 28, 1921, on an application filed by me. In placing a blank in position, the operator pushes the blank down on the die block 22 and slides it forwardly, the fore-part being engaged by the gages 24 which spread and hold the blank at the ball line, the heel end portion being engaged by the gages 26 which move the blank into proper alignment laterally, and the end of the heel portion being brought into contact with the heel gage 28 which limits longitudinal movement of the blank.

The heel gage 28 is mounted in the enlarged portion 112 of a sleeve 114 (Fig. 6) and is provided on its lower surface with a rack 116 which is in mesh with a pinion 118 mounted on a shaft 120 supported within the sleeve 114. To effect a movement of the heel gage radially of the block, the shaft 120 is rotated by means of the pin-and-slot construction illustrated in Figs. 6 and 7. A plunger 122 is adapted to slide within the shaft 120 but is normally locked against rotative movement by means of a pin 124 extending through an oblique slot 126 of the shaft and contacting with the walls of a longitudinal slot 128 in the collar 130 which is mounted on the shaft 120. Consequently, longitudinal movement of the plunger 122 and pin 124 will cause rotation of the shaft 120 and movement of gage 28 by reason of the contact of the pin with the walls of the oblique slot 126. The height of the gage 28 above the die block 22 is adjusted by means of a set-screw 131 mounted on the frame and arranged to bear on the outer surface of the gage supporting portion 112 of the sleeve 114. Movement of the screw 131 effects a rotation of the sleeve 114 to adjust the gage toward or away from the surface of the block.

To provide for convenient adjustment of the heel gage 28 to various lengths of blanks, a lever 132 is arranged for actuating the plunger 122 by means of a rock-shaft 134 and a forked member 136 engaging a grooved collar 138 on the end of the plunger. During the positioning of a blank, the plunger 122 and consequently the gage 28 is held in adjusted position by means of a toothed rack 140 and a pawl 142 on the hand lever 132.

To avoid contact with the operating die, it is necessary that the gages 26 and the heel gage 28 be retracted from engagement with the blank on the die block 22 early in the cycle of the machine operations.

The mechanism for retracting the gage 28 comprises a cam 144 (Figs. 1 and 2) mounted on the shaft 38 operating a cam roll 146 to rotate a bell crank 148 to raise a link 150 which is connected to the collar 130 by means

of the arm 152. Rotation of the collar 130 in a clockwise direction causes a similar rotation of the pin 124, and since longitudinal movement of the plunger 122 is prevented by the latch device 140-142, the shaft 120 is rotated to retract the gage 28. As rotation of the collar 130 continues, a pin 154 on a bell-crank 156 will be engaged in a recess 158 in the flange of the collar 130 causing rotation of the bell-crank 156. Since the latter is secured to the sleeve 114 by means of the bolt 160, rotation of the bell-crank causes rotation of the sleeve 114, and gage 28 is rotated away from the surface of the die block. The gage is held in its rotated position during the dieing-out operation by means of a spring latch 162 which engages a lug 164 on the bell-crank 156. After an operation of the die, the roll 146 reaches the low portion 166 of the cam 144 and a spring 168 depresses the link 150 causing rotation of the collar 130 in a counter-clockwise direction with the result that the gage 28 is extended nearly its whole length out of its supporting member 112. Upon further depression the link 150 contacts with a plate 170 attached to the latch 162, tripping the latch and permitting a spring 172 to rotate the bell-crank 156 which causes rotation of the sleeve 114 and of the gage 28, while in its extended position, back toward the die block. On still further rotation of the cam 144, the cam roll 146 begins to rise on the cam surface, again raising the link 150 to cause a retraction of the gage 28. The movement of the gage 28 in the manner above described is for the purpose of insuring the removal of the chip or scrap cut from the heel portion of the blank. To this end, the outer end portion of the gage is formed into a hook as shown at 174 (Fig. 8) which, when the gage is rotated back to its position on the die block, extends beyond the line of cut of the die, the subsequent retraction of the gage causing the hook portion 174 to engage and remove the chip which falls from the die block 22 into a slide 176.

Retraction of gages 26 is accomplished by rotating the shaft 104 to move the set-screw 102 inward against the lug 106, thus causing movement of the gages 26 away from the blank. The shaft 104 is rotated by means of a forked arm 178 which is raised by contact with a connection 180 on the link 150, at the same time that the link causes retraction of the heel gage 28. When the connection 180 is depressed with the link 150, the spring 100 acts to return the gages 26 inwardly to their original position.

The mechanism for actuating the pawl 88 for rotating the die block comprises links 182, 184, and a bell-crank 186 which is loosely mounted on the sleeve 114. Connected to the bell-crank 186 is a link 188 which is operated by the bell-crank 148 in a manner similar to the operation of link 150. Depression

of the link 188 operates the links 182 and 184 in such manner as to retract the pawl 88 over the rack 86. At the end of the cycle of operation, when the link 188 is depressed through action of spring 168, the pawl 88 is engaged with the rack teeth causing rotation of the die block 22 through a small arc in a clockwise direction.

To hold a blank securely on the die block 22 when the gages 26 and 28 have been retracted, the presser foot 30 is provided. The presser foot is formed of sheet metal and is supported on a rock-shaft 190 which is actuated by means of a link 192 and a link 194 (Fig. 1) operatively connected to the treadle 48. Depression of the treadle 48 to initiate operation of the die turret simultaneously causes depression of the presser foot 30 to hold the blank in position during the dieing-out operation. When the treadle is released by the operator, a spring 196 operates to raise the treadle and with it the link 194, thus rotating the link 192 and raising the presser foot 30 from contact with the blank.

Having illustrated and described the preferred embodiment of the invention, that which is claimed as new is:—

1. A cutting machine comprising a work support, a plurality of open dies of different sizes shaped for dieing out the heel ends of unattached blocked soles, a carrier for the dies operable to move any selected die from an inoperative position to a position in operative relation to the work support, members for locating a sole on the work support in alignment with the selected die, and means for effecting relative movement of the selected die and the work support to perform a dieing-out operation.

2. A cutting machine comprising a work support, a plurality of open dies of different sizes adapted for dieing out the heel ends of unattached blocked soles, said dies being arranged to provide for movement of any selected die from an inoperative position to a position in operative relation to the work support, members for locating a sole upon the work support in operative relation to the selected die, and means for effecting relative movement of the work support and a selected die to perform a dieing-out operation.

3. A cutting machine comprising a work support, a plurality of open dies of different sizes adapted for dieing out the heel ends of unattached blocked soles, and having their ends turned outwardly to cut off the waste resulting from the dieing-out operations, means operable to move any selected die into operative relation to the work support, members for locating a sole upon the work support in operative relation to the selected die, and means for effecting relative movement of the work support and the selected die to perform a dieing-out operation.

4. A cutting machine comprising a work

support, gaging means for positioning an unattached blocked sole upon the work support, a plurality of open dies of different sizes adapted for dieing out the heel ends of unattached blocked soles, a carrier for the dies operable to move any selected die from an inoperative position to a position in operative relation to a sole positioned on the work support, and power means for reciprocating the carrier to cause the selected die to perform a dieing-out operation.

5. In a machine of the class described, a work supporting member, a turret constructed and arranged to carry a plurality of dies, means for selectively positioning one of the dies for operation on the work, power means for causing relative movement of the turret and work-supporting member, and means operating automatically for locking the power means against operation in the event that the selected die is not properly positioned for operation on the work.

6. In a machine of the class described, a work supporting member, a tool holder constructed and arranged to carry a plurality of tools and movable toward and away from said member, means for selectively positioning one of the tools for operation on the work, means for locking the selected tool in operative position, and means for preventing operation of the machine when no one of the tools is in position for operation on the work.

7. In a machine of the class described, a work supporting member, a turret constructed and arranged to carry a plurality of dies and movable toward and away from said member, means for selectively positioning one of the dies for operation on the work, means for locking the die in operative position, starting means for initiating a reciprocation of the turret, and means operable when no one of the dies is locked in operative position for preventing actuation of the starting means.

8. In a machine for operating on sole blanks, a die block, a turret supporting a plurality of dies, a power operated means for moving the turret toward and away from the block, means operable for selectively moving one of the dies into operative position relative to the block, means for locking the die in operative position, and means operative upon failure of operation of the locking means to prevent actuation of the power operated means.

9. A machine for operating on sole blanks having, in combination, a die, a work support, members for positioning a blank on the support, means for causing relative movement of the die and support to effect a trimming operation on the blank, means operable during such relative movement to retract said members into inoperative position, and means operable to move one of said members in such manner as to insure the separation

of the trimmed blank from the material trimmed from the blank.

10. In a machine for operating on sole blanks, a work support, a die, members for actuating the die to perform an operation on a blank positioned on the support, gages for positioning the blank on the support and mechanism responsive to the actuating members for operating one of the gages to remove the chip cut from the blank.

11. In a machine for operating on sole blanks, a work support, gages for positioning a blank on the work support, means operable to cause a dieing-out operation on the blank, and means operable to actuate one of the gages in such manner as to remove from the work support the material cut from the blank.

12. In a machine of the class described, 20 a die, a die block, means for positioning a blank on the block, means for causing a dieing-out operation of the die, means for retracting the positioning means prior to the dieing-out operation, means for returning 25 the positioning means to a point on the blank beyond the line of cut of the die, and means for retracting the positioning means over the line of cut in such manner as to remove surplus material from the blank.

30 13. In a machine for operating on sole blanks, a die block, a die, means for causing a dieing-out operation of the die and die block, a heel gage for positioning a blank on the block, means for retracting the gage 35 previous to the dieing-out operation, and means for moving the gage subsequent to the dieing-out operation in such manner as to remove the material cut from the blank.

40 14. In a machine of the class described, a work support, a heel gage for positioning a blank on the support, the gage having a rack on the lower surface thereof, a shaft carrying a pinion meshing with the rack for effecting movements of the gage relative to 45 the support, a manually operable plunger constructed and arranged to adjust the gage to position different sizes of blanks, and means automatically operable to retract the gage prior to an operation on the blank.

50 15. In a machine for operating on sole blanks, a work support, a die, members for positioning a blank on the support, starting means for initiating an operation of the die on the blank, means for retracting the positioning members when an operation on the blank is initiated, a presser foot for holding the blank on the work support during such time as the positioning members are retracted, and connections between said starting means and said presser foot for actuating said presser foot simultaneously with the starting means.

60 16. A cutting machine comprising a work support, a plurality of dies of different sizes

adapted for performing operations upon the heel ends of unattached blocked soles, said dies being arranged to provide for movement of any selected die from an inoperative position to a position in operative relation to the work support, members for positioning a sole upon the work support, means for adjusting the positioning members in accordance with the size of the selected die in order to insure alignment of the sole with the selected die, and means for effecting relative movement of the selected die and work support to perform a dieing-out operation upon the sole.

70 In testimony whereof I have signed my name to this specification.
